UNITED STATES PATENT OFFICE.

FRANCIS W. TULLY, OF BROOKLINE, MASSACHUSETTS.

APPAREL.

Application filed December 10, 1917. Serial No. 206,389.

This invention relates to apparel of the class adapted to be laundered. Custom and habits of neatness prescribe for both men and women garments of the general type of shirts and waists adapted to be refreshed and cleansed by laundering. In many occupations neatness of appearance is essential to the wearer but is maintained with difficulty owing to the necessities of the occupation. During a single day workers in stores and in shops, amanuenses, and clerks and other workers in many varieties of occupation find the exposed portions of their garments subject to soiling unavoidable from the nature of the occupation and damaging to their appearance and sense of neatness. In the comparatively poorly paid occupations the expense of maintaining the fresh appearance of laundered linen is in many cases unduly burdensome. In times of shortage and high expense of textiles the capital of such clothes required of even the very poor in the occupations mentioned is large, and a burden upon the supply for more necessary uses. It is therefore desirable to provide a class of garments adapted to resist casual soiling, but still capable of being cleansed at sufficiently short intervals to maintain actual cleanliness. Principal objects of this invention are to provide apparel of the class indicated which shall be capable of being laundered but which shall resist soiling, spotting and deformation of surface by wetting. I am aware of the various rubber, celluloid and other imitation laundered fabric parts and attachments for garments which have heretofore constituted the best known approach to the class of garment in question, but the said imitation collars, cuffs, etc., fail of their purpose because of their distinctive and essential falsity of appearance and because they are necessarily detached objects, incapable of being laundered with the remainder of the garment.

Further objects of the invention are therefore to provide garments and sections of garments having only at the portions subjected to wear and soiling a transparent or translucent waterproof, cementitious, plastic finish, application or addition to the fabric, and having the characteristic of displaying the texture and color of the treated portion of the cloth, but preventing the penetration or holding of water, dirt and other soiling agents.

In the accompanying drawings showing illustrative species of garments and sections of garments illustrative of the genus comprised by the invention,

60

Figure 1 is an elevation of a shirt embodying the invention;

Figure 2 is an elevation of the bosom portion of a stiff shirt embodying the invention;

65

Figure 3 is a detail of a wrist band;

Figure 4 is an elevation of a cuff;

Figure 5 is an elevation of a cuff intended to be detached and representing a stage product of the manufacture;

Figure 6 is a section on line 6—6 of Fig. 5;

70

Figure 7 is an elevation of a folded collar illustrating the invention;

Figure 8 is a section on the line 8—8 of Fig. 7;

Figure 9 is a section on the line 9—9 of Fig. 2, illustrating a stage in the manufacture;

75

Figure 10 is a section on said line illustrating the complete product;

Figure 11 is a section on line 11—11 of Fig. 1 showing a soft folded cuff.

80

Figure 12 is a view illustrating the cuff shown in Fig. 11 as a stage product; and

Figure 13 is a section similar to Fig. 11, illustrating another construction.

85

Referring now to Fig. 1, the shirt [or woman's shirtwaist] illustrated in said figure may be provided with a bosom portion 1, collar 2 and cuffs 3 of any usual form or construction. As usual, these parts may be in part of double layers or multi-ply; the collar 2, for instance, being composed of three or more layers and the cuffs 3, as illustrated in Fig. 11, being composed of two or more layers, the outer layers *a* being of the fabric of the body of the garment, an inner layer *b* being a stiffener or filler fabric; but any other known or usual construction may be employed.

90

In the man's shirt shown in Fig. 2, the bosom portion 5 may be of the stiff type, and the garment may be intended to be worn with a detachable collar and to be provided with a collar band 6 of usual construction except as hereinafter specified.

100

The parts so far mentioned are all exposed parts liable to be soiled or rumpled in use, and in accordance with this invention these parts are treated by spreading, spraying, padding or dipping, or by application with a brush or other applicator, and if desired by the subsequent action of rolls, with

105

110

a translucent or transparent, waterproof, cementitious substance, preferably adapted to resist the action of moderate heat, such as laundry ironing, and adapted to resist 5 the action of the usual soapy or alkaline wash-water employed in laundering operations.

Material for the finishing, coating or protecting operation as indicated may be any 10 material adapted to secure the specified results, but I prefer to employ a plastic, cementitious, adhesive solution of cellulose in a solvent. Cellulose acetate dissolved in acetone of a limpid consistency but having 15 sufficient cellulose acetate in solution to leave a substantial residue upon evaporation of the acetone solvent is an advantageous and preferred material. In some cases I may employ, however, other cellulose compounds 20 such as cellulose nitrate in a suitable solvent, such as amyacetate or an ether. And in some cases I may treat the outer face of a section, such as the collar 2 or the bosom 5, with the cellulose acetate solution, the filler 25 or the inner or back face or both, with a cellulose nitrate solution, this procedure being adapted to take advantage of a difference in cost between the respective treating solutions, and the superior resistance to heat 30 of the application containing cellulose acetate.

Fabric of the usual materials for shirts, shirt-waists and the like subjected to the treatment above described, and then subjected 35 to drying in a flat state with or without the application of heat and flattening pressure presents the appearance of having been starched and ironed. The color and texture of the fabric is not altered but is 40 displayed beneath the transparent or translucent applied material, which when finished has a matte surface. If desired, a pigment may be mixed with the application. The application may be increased if desired to 45 form a perceptible coating as by drying the first application and repeating the application until the dried application is sufficiently heavy. The object is not to stiffen the cloth to board-like stiffness, or necessarily to fill 50 its textural interstices, but to impregnate and protect the component yarns so as to render the fabric impermeable to moisture except under prolonged agitation and soaking, and so as to provide a finished material 55 offering little frictional hold for ordinary types of soil and dirt. Fabrics so treated is adapted to be cleansed with a damp cloth unless the soiling is very thorough. Fabric so treated may be laundered 60 by the usual methods without starching, flat drying and pressing with a comparatively cold iron being sufficient to restore the flatness and good appearance of the treated parts after washing. But as hereinafter described, parts desired to be very stiff pass 65

through the washing operation without losing their stiffness or flatness.

Details of construction may vary with the particular garment, but certain changes in the structure of the garment are facilitated by the treatment above described. As shown in Fig. 9, a shirt bosom, cuff, collar, or the like may be built up to stiffness from layers of the cloth or material like the body of the garment, as a' , and a 70 filler of a coarser cloth or preferably of hard paper of good quality as shown at f . Such part of the garment may be assembled by turning in the edges of the face plies a' , a' , placing a filler f between them and then sewing 75 the edges, but I prefer to first to saturate the filler and treat the face plies with the treating plastic and then assemble the whole as shown at Fig. 10, with the aid of pressure, and if desired, pressure and heat, 80 so that the plies are cemented together.

Such a section, as illustrated in Figs. 9 and 10, may be sewn in place after treatment, but the treatment of the fabric of which it is composed makes sewing somewhat more 85 difficult, and I therefore prefer to leave the edges of such a section, illustrated by the edge d of the cuff c illustrated in Fig. 5, without any coating, and then apply the treated cuff to the garment and sew on as 90 usual. The sewed seam may be treated with some of the solution and dried in a flat state if desired.

For a soft or turnover collar or cuff as typified by the cuff 3 of Figs. 1 and 11, the 95 face plies a and the filler ply b may be separately treated and then assembled, or may be treated and dried while the plies are spaced apart.

The same steps may be taken to make the 100 collar 7, such as shown in Figs. 7 and 8, and the cuff 3 if desired may be subjected to the same partial treatment as illustrated for the cuff c in Fig. 5, the portion d' of Fig. 12 of the cuff being left without any coating until 105 it is sewed in place on the garment.

When the material of the shirt or other garments is relatively heavy, as of cheviot shirting, two plies may be sufficient for a 110 cuff or other part and the structure may be that illustrated in Fig. 13 comprising the face plies a^2 , a^2 , only, which may or may not be stuck together by the coating material.

It will be readily understood by those skilled in the art that the form of the garment may vary widely; for instance, a shirt such as shown in Fig. 1 may have a sleeve ending in a wrist band w as shown in Fig. 3 and a separate cuff c' may be provided for attachment thereto in the usual manner, both the wrist band w and the cuff c' being treated.

I have found in practice that the resistance to moisture and soiling of garments treated as described is accompanied by an in-

creased durability of the exposed parts, which I ascribe to the fact that wear upon the edges and folds of a garment is largely due to abrasion while wet, a dry fabric resisting wear at these places. The described treatment also adds to the tensile and wear-resistant strength of the material by binding together the fibres of which it is composed.

10 When I have herein referred to the waterproof cementitious protective substance as "translucent" I intend the word to be taken in its generic significance, as inclusive of substances transmitting light, whether or not the light is diffused.

What I claim is:

1. A textile fabric garment of the class adapted to be laundered by washing and ironing having parts only protected from wear, rumpling and rapid soiling by including therein an application of a translucent material characterized by resistance to the action of soap or alkaline washing liquids, the remainder of the garment being absorbent and the whole washable, the treated portions visually displaying the texture and coloring of the untreated cloth.

2. A textile fabric garment of the class adapted to be laundered having parts only protected from wear, soiling, rumpling and the penetration of moisture by the impregnation of the interstitial spaces of the component yarns with a translucent, waterproof cementitious material insoluble in soapy or alkaline washing liquids, and adapted to resist disintegration by the action of moderate heat, such as laundry ironing, substantially the untreated color and texture of the portion of the fabric treated being visually distinguished at the treated portions.

3. A textile fabric garment of the class adapted to be laundered having only those parts exposed to rapid wear, soiling, rumpling and the penetration of moisture in use protected by the impregnation of the interstitial spaces of the component yarns of said parts only with a cellulose compound characterized by retention of its specific properties under moderate heat and pressure, such as laundry ironing, the remaining parts of the garment being untreated.

4. A textile fabric garment of the class adapted to be laundered having only those parts exposed to rapid wear, soiling, rumpling and the penetration of moisture in use protected by the impregnation of the interstitial spaces of the component yarns of said parts only with the residue of a solution of

cellulose acetate left by evaporation of the solvent.

5. A garment section having a portion only thereof impregnated with a translucent waterproof cementitious material and displaying the color and texture of the untreated cloth, said section having a portion untreated, whereby sewing in the untreated portion subsequent to treatment is facilitated.

6. A textile fabric garment of the class described having a multiply section stiffened by impregnation with a translucent waterproof cementitious plastic material causing the plies to adhere to each other.

7. A garment of the class described having a multiply section including face plies of cloth and a filling ply saturated with a translucent waterproof cementitious material.

8. A textile fabric garment for wear as a shirt having portions only of the garment, locally bearing an impregnation of a translucent cementitious waterproof, heat resisting substance adapted to protect said portions from rapid soiling, rumpling, and the absorption of moisture, the garment being adapted to be cleansed by washing and smoothed by ironing.

9. Web material having a permanent stiffness in portions thereof produced by treatment of the web subsequent to the formation of the latter, and having other portions thereof in a soft and pliable state adapted to facilitate folding.

10. A fabric of uniform original texture, which has been made permanently stiff except at predetermined folding or cutting lines.

11. An article of wearing apparel made in whole or in part of separate layers or plies of fabric secured together by an intermediate layer or layers of binding material, at least two layers or plies of fabric extending beyond the main united portion of the fabric, said layers being untreated with the binding material, and turned in and secured to form the edge binding.

12. An article of wearing apparel made in whole or in part of separate layers or plies of fabric, secured together by an intermediate layer or layers of binding material, the outer layers or plies of fabric extending beyond the inner layer or layers and forming a divided edge which is turned in and stitched to form the edge binding.

Signed by me at Boston, Massachusetts, this 7th day of December, 1917.

FRANCIS W. TULLY.
